United States Patent Office

Des. 180,541
Patented July 2, 1957

180,541

WRAPPING PAPER OR SIMILAR ARTICLE

Jean Alexandre, Paris, France, assignor to Societe Anonyme Parfumerie Violet, Paris, France, a corporation of France

Application March 9, 1956, Serial No. 40,523

Term of patent 14 years

(Cl. D59—2)

The drawing shows a plan view of a sheet of wrapping paper illustrating my design, a complete unit of said design being embraced by the section lines, which unit is used as a repeat.

I claim:

The ornamental design for a wrapping paper or similar article, substantially as shown.
